UNITED STATES PATENT OFFICE.

SETH H. LEAVENWORTH AND JOSEPH T. HOMAN, OF CINCINNATI, OHIO, ASSIGNORS TO THE HOMAN SILVER PLATE COMPANY, OF SAME PLACE.

DESIGN FOR A CANDELABRUM.

SPECIFICATION forming part of Design No. 26,277, dated November 17, 1896.

Application filed July 20, 1896. Serial No. 599,977. Term of patent 14 years.

To all whom it may concern:

Be it known that we, SETH H. LEAVENWORTH and JOSEPH T. HOMAN, citizens of the United States, residing at Cincinnati, in the county 5 of Hamilton and State of Ohio, have invented and produced a new and original Design for a Sick-Call Outfit; and we do hereby declare the following to be a full, clear, and exact description of the same, reference being had 10 to the accompanying drawings, which form a part of this specification.

Our invention comprises a new and original design for a combined candelabrum and water-font, such as used by the Catholic 15 clergy in making what are generally known as "sick-calls," the special features of said design being clearly shown in the annexed drawings, in which—

Figure 1 is a front elevation of a combined 20 candelabrum and water-font embodying our design. Fig. 2 is a plan of the water-font detached from said candelabrum.

Referring to Fig. 1, A represents a base supporting an ecclesiastical crucifix B, near the foot of which is a shell-shaped water-font 25 C, a plan of the latter being seen in Fig. 2. Projecting laterally from the crucifix are arms D D' of a candelabrum, said arms being composed of scroll ornaments terminating at their upper ends with conventional forms of acan- 30 thus-leaves, as seen at d d'.

E E' are ordinary candle-holders carried by these arms D D' and having their bases surrounded by the leaves d d'.

F represents a combined scroll and leaf or- 35 nament above the junction of the crucifix B and its arms D D'.

We claim as our invention—

The design for a combined candelabrum and water-font, as herein shown and de- 40 scribed.

In testimony whereof we affix our signatures in presence of two witnesses.

SETH H. LEAVENWORTH.
JOSEPH T. HOMAN.
